United States Patent Office.

CHARLES E. ROPER, OF CANTON, OHIO.

Letters Patent No. 67,587, dated August 6, 1867.

IMPROVEMENT IN MACHINERY FOR CUTTING BEVEL-GEARs.

The Schedule referred to in these Letters Patent and making part of the same.

TO ALL WHOM IT MAY CONCERN:

TO ALL WHOM IT MAY CONCERN.—
Be it known that I, CHARLES E. ROPER, of Canton, in the county of Stark, and in the State of Ohio, have invented certain new and useful Improvements in Machine for Cutting Bevel Gear-Wheels; and do hereby declare that the following is a full, clear, and exact description thereof, reference being had to the accompanying drawings, and to the letters of reference marked thereon. In the annexed drawings, making part of this specification—

Having thus fully described my invention, what I claim as new, and desire to secure by Letters Patent, is—

1. The combination of the slide L, the sliding platform M, the box N, and the slide O, and used in the manner and for the purpose set forth.
  2. The combination of the piston B, box C, plate D, arm E provided with the tool R, the bar F, and the bar G, and arranged substantially as and for the purpose set forth.

standard G, constructed and arranged substantially as and for the purpose I have herein set my hand this 20th day of May, 1867.

CHAS. E. ROPER.
